(57) **CLAIM**

The ornamental design for a gas analyzer module, as shown
and described.

DESCRIPTION

FIG. 1 is an end, side and top perspective view of a gas
analyzer module, showing my new design;

FIG. 2 is an opposite end, side and top perspective view
thereof,

FIG. 3 an end, opposite side and bottom perspective view
thereof (a left side thereof is a mirror view of the right side);
and,

FIG. 4 is an end, opposite side and top perspective view
thereof.
